JUICE EXTRACTOR

William de Back, Niagara Falls, N. Y., assignor
to Chisholm-Ryder Company, Incorporated,
Niagara Falls, N. Y., a corporation of New York

Application June 27, 1941, Serial No. 400,028

5 Claims. (Cl. 100—48)

This invention relates to a juice extractor and more particularly to a juice extractor of the screw type in which the materials are compressed against a screen while being conveyed axially by the screw and the pomace is discharged through an annular opening of adjustable size at the trailing end of the screw.

One of the principal objects of this invention is to provide such a juice extractor which is provided with a screw of large diameter to obtain high capacity and which is also capable of extracting juice from all types of pulpy materials. It was found, especially with pulpy materials, that increasing the diameter of the screw strikingly increased the tendency of the pomace to resist discharge through the annular opening at the trailing end of the screw and that this pomace would compact and stop the rotation of the screw. The present invention eliminates this undesirable condition.

Another object is to provide such a juice extractor which will operate efficiently and smoothly at all times, this being obtained by supporting one end of the screw by means of a self-aligning ball bearing.

Another object is to provide such a juice extractor in which simple and readily accessible means are provided for conveniently adjusting the size of the annular pomace discharge opening at the trailing end of the screw.

Another object is to provide, in combination with such adjusting means, an easily readable gage or index for determining the size of the annular pomace discharge opening.

Another object is to provide an automatic relief means for preventing an accumulation of pomace at the trailing end of the screw from clogging the apparatus and stopping the rotation of the screw.

Other objects of the invention are to provide such a juice extractor which is of simple construction, efficient in operation and will stand up under conditions of severe and constant use without getting out of order or requiring repairs.

In the accompanying drawings:

Fig. 1 is a vertical central section, partly in elevation, of a juice extractor embodying my invention.

Fig. 2 is an enlarged fragmentary, vertical, central section at the discharge end of the screw.

Fig. 3 is a fragmentary vertical section, taken on line 3—3, Fig. 2.

The juice extractor shown is of the same general type as that set forth in the McNitt Reissue Patent No. 21,449, dated May 14, 1940, having a

pair of end heads 5, 6 which are mounted on a base or bed 7 which can be suitably supported on legs 8. The end head 5 is preferably in the form of a casting formed to provide a pomace outlet chamber 9, which is shown as open at its bottom to permit the pomace to fall into a suitable receptacle or waste duct (not shown). The end head 6 is formed to provide an inlet chamber 10 to receive the tomatoes or other materials being handled. For this purpose the upper end of the chamber 10 is open and carries a hopper 11 into which a substantial quantity of the materials being handled can be placed, these materials falling by gravity into the inlet chamber 10. The outer wall of the end heads 6 is formed to provide a bearing 15, the bearing 15 being provided with a stuffing box 16 accessible from the exterior of the apparatus. The outer wall of the end head 5 is formed to provide an integral outwardly extending collar or boss 17 which is provided with a bore 18, and this bore is provided with a stuffing box 19 which is accessible from the interior of the pomace discharge chamber 9.

25 The juice extractor is shown as having a large diameter screw 20 having a projecting shaft 21 at one end arranged in the bore 18 of the boss 17 and provided beyond this bore with an extension 22 of reduced diameter providing an annular shoulder 23. The bore 18 is not, however, the bearing surface for the shaft 21, this bore being slightly oversize and this shaft being journaled in a self-aligning bearing as hereinafter described. At its opposite end the screw 20 is 35 provided with a drive shaft 24 journaled in the bearing 15 by means of which the screw is turned to convey the materials from the inlet chamber 10 toward the outlet chamber 9. Any suitable drive (not shown) can be provided for the drive 40 shaft 24.

The screw 20 is shown as provided with a thread 25 which extends continuously from the inlet chamber 10 to a point adjacent the discharge end of the screw. This thread defines a 45 channel 26 which is of considerable depth at the feed end of the screw and becomes progressively shallower toward the discharge end of the screw. This channel or groove 26 terminates short of the extreme end of the body of the screw 25 so as to provide an annular end 27 projecting coaxially beyond the discharge end of the screw, this annular projecting end 27 being beveled, as indicated at 28.

The edges of the thread 25 contact with the 50 internal face of a screen 30, this screen being

preferably reinforced by an external frame 31 of skeleton form. The outer edges of the screw 20 are shown as being parallel with the axis of the screw and hence the screen 30 and skeleton frame 31 are of cylindrical form. However, it will be understood that these edges, the screen and the skeleton frame can be slightly tapered. The screen 30 and its reinforcing frame 31 are preferably made in two semi-cylindrical sections as described in said McNitt reissue patent to permit of convenient access to the screw 20 for the purpose of cleaning.

The opposite ends of the cylindrical screen 30 and its reinforcing frame 31 are suitably supported on the end heads 5 and 6 and the inner wall of the end head 6 is provided with a round opening 32 leading from the inlet chamber 10 into the screen 30. The inner wall of the end head 5 is similarly provided with a round opening 33 leading from the interior of the screen 30 into the pomace discharge chamber 9, this opening 33 being preferably beveled, as indicated at 34, complementary to the bevel 28 on the end of the screw 20 to provide a tapered annular opening 35 controlling the discharge of the pomace by the screw into the pomace discharge chamber 9. This discharge can be controlled by the axial adjustment of the screw 20 as hereinafter described.

The juices expressed through the screen 30 are caught in a pan 36, having inclined sides leading to a duct 37, through which the juices flow by gravity to be subsequently processed.

The screw, as above described, has been found to be entirely satisfactory in expressing juice from tomatoes when the screw was of comparatively small diameter, that is, in the order of six inches. When, however, in order to obtain increased capacity, the diameter of the screw was increased, as with a screw having a diameter of twelve inches, difficulty was encountered through the congestion of pomace in the annular space 35 between the tapers 28 and 34 and in the groove 26 between the trailing convolutions of the thread 25. Especially with very pulpy materials, the rate of discharge of the pomace through the tapered opening 35 was slower than the rate of feed of the screw to this discharge opening so that the pomace would necessarily build up in advance of the pomace discharge opening 35 and in a short time compact sufficiently to stop the rotation of the screw.

To avoid this, the screw 25 is shown as provided with an additional thread 40 in the center of the groove 26 between the edges forming the discharge convolution of the thread 25. This auxiliary thread 40 gradually rises, at its leading end 41, from the bottom of the groove 26 to a point of contact with the screen 30. From this point it continues in contact with the screen 30 for approximately one complete convolution and its trailing end 42 terminates at the enlarged part of the tapered annular end 27 of the screw in the same manner as the trailing end of the main thread 25. This auxiliary thread 40 provides an auxiliary propelling medium at the discharge end of the screw and approximately doubles the force imposed upon the pomace immediately in advance of the pomace discharge opening 35. Hence it will be seen that this auxiliary thread serves to relieve congestion of the pomace in advance of the pomace discharge opening 35 and overcomes the difficulties arising from such congestion as above discussed. Since the auxiliary thread 40 is arranged in the

center of the channel 26, it will be seen that its trailing end is arranged opposite the trailing end of the main thread 25. It will be understood, of course, that if additional force is required to force the pomace through the discharge opening 35, more than one auxiliary thread 40 could be employed in the groove 26 at the trailing end of the screw and the use of such additional auxiliary threads is within the scope of the present invention.

Means are provided at the end of the shaft 21 for journaling this shaft; for adjusting the effective size of the pomace discharge opening 35 through axial positioning of the screw 20; and to yieldingly permit axial movement of this screw in the event of undue congestion of pomace in the opening 35, thereby to provide an automatic relief of the size of the opening 35. These means are preferably constructed as follows:

20 Mounted on the reduced end portion 22 of the shaft 21 is a small collar 45, this collar having an annular outwardly projecting flange 46 arranged against the annular shoulder 23 of the shaft 21. Also mounted on the reduced end portion 22 of the shaft 21 is a sleeve 47, this sleeve having a reduced end portion 48 abutting against the collar 45 and providing an annular shoulder 49. A washer 50 is fitted around the reduced end portion 22 of the shaft 21 against the outer end of the sleeve 47, this washer serving as the end abutment of a helical compression spring 51. The other end of this helical compression spring 51 bears against a nut 52 which is screwed onto a threaded extension 53 of the shaft 21, this extension being in the form of a cylindrical cap having a bore 54 fitting over the end of the reduced end portion 22 of the shaft 21 and secured thereon by means of a pin 55. The nut 52 is maintained in adjusted position by a lock nut 56.

40 Mounted on the reduced portion 48 of the sleeve 47 between the shoulder 49 and the flange 46 of the collar 45 is the inner race 60 of a self-aligning ball bearing, the outer race 61 of which is provided with an inner spherical bearing face which bears against two annular series of balls 62, each of these series of balls 62 riding in a peripheral groove provided in the inner race 60. It will therefore be seen that this bearing supports the shaft 21 in centered relation to the slightly oversize bore 18 of the collar 17 formed integrally with the end head 5; is self-aligning so as to permit the shaft 21 to properly aline itself; and also provides a thrust bearing to take the longitudinal thrust of the screw 20.

55 The outer race 61 of this self-aligning ball bearing is held in the enlarged bore 65 of an adjusting sleeve 66 which is slidably and rotatably fitted on the outer end of the collar 17 which is formed integrally with the end head 5. The inner end of this adjusting sleeve 66 is threaded, as indicated at 67, and is screwed onto the enlarged inner threaded end 68 of the integral collar 17. The adjusting collar 66 is turned by means of a large hand wheel 69 which can be formed integrally with this adjusting sleeve. The outer race 61 of the self-aligning ball bearing is held in position in the bore 65 by a retaining collar 70, this retaining collar having an outwardly extending annular flange 71 which is secured by screws to the end face of the adjusting collar 66; an axial projecting end flange 71a which bears against the corresponding end of the outer race 61 of the self-aligning ball bearing; an opposite axially projecting flange 72 which forms a support for a cap 73 which en-

closes the end of the extension 22 of the shaft 21 and the associated helical compression spring 51; and a radially inwardly projecting flange 14 which loosely fits the sleeve 47 and is spaced from the races 60 and 61 of the self-aligning roller bearing so as to provide an annular space for the reception of an annular grease seal 75 of any suitable form.

The longitudinal position of adjustment of the adjusting sleeve 66 can be readily ascertained at all times. For this purpose a series of spaced annular markings 76 are provided on the adjusting sleeve which markings can be calibrated or numbered in any desired manner to indicate the corresponding size of the pomace discharge opening 35. These markings traverse a stationary pointer 78 mounted on an arm or bracket 79 secured to the outer wall of the end head 5, as best shown in Figs. 1 and 3.

Similarly detent means are provided for holding the adjusting sleeve 66 in any position of adjustment. For this purpose the sleeve is provided at its inner end with an annular series of axially extending shallow grooves 80 which receive the detent 81 of a spring finger 82, this spring finger being mounted on the end head 5 and being flexible in a direction radial of the adjusting sleeve 66. The detent 81 is shown as provided by bending the end of the spring finger 82 into rounding form.

In operation the materials to be handled, such as tomatoes which have been passed through a chopping box, are placed in the hopper 11 from which they drop by gravity into the inlet chamber 10. This material is picked up by the leading end of the screw 20, this screw forcing the material against the screen 30 so that the juices are expressed through the perforations of this screen, these juices being caught in the pan 38 and flowing through the conduit 37 for further processing. As the depth of the groove 26 of the screw becomes progressively shallower toward its discharge end, the material is discharged by the screw in the form of pomace through the annular pomace discharge opening 35 into the pomace receiving chamber 9, this pomace falling through the opening bottom of this chamber into a suitable receptacle or waste line (not shown). The degree of juice extraction obtained is determined by the spacing of the conical faces 28 and 24 of the screw and end head 5, respectively. This spacing is adjusted by the longitudinal positioning of the screw 20 through the adjustment mechanism forming a feature of the present invention.

To effect such adjustment, the operator turns the hand wheel 69 which is formed integrally with the adjusting screw sleeve 66. Since this screw is threadedly mounted on the collar or boss 17, turning this adjusting screw 66 effects its adjustment axially along the shaft 21 of the screw 20. The adjusted position of this adjusting sleeve 66 is readily determined at any time through the pointer 78 which traverses the calibrated graduations 76 provided on the adjusting sleeve 66. The yielding detent 81 also serves to drop into the corresponding one of the shallow grooves 80 provided on this adjusting sleeve and hence hold the adjusting sleeve against rotation from any position to which it has been set by the manipulation of the hand wheel 69.

The axial movement of the adjusting sleeve 66 so effected by turning the hand wheel 69, effects a corresponding axial movement of both races 60 and 61 of the ball bearing housed by this ad-

justing sleeve, this bearing being designed to act both as a thrust bearing and also to rotatively support the extension 22 of the screw shaft 21. This axial movement of the inner race 60 effects a corresponding movement of the sleeve 47 and collar 45, these parts being held in fixed relation to the extension 22 of the screw shaft 21 by the helical compression spring 51. This axial movement of the sleeve 47 and collar 45 thereby effects a corresponding adjustment of the end 22 of the screw shaft 21 and hence of the screw 20. It will therefore be seen that the axial spacing of the conical discharge surface 28 of the screw 20 with reference to the fixed conical surface 34 of the end head 5 can readily be effected by turning the hand wheel 69 in one direction or the other, the size of the opening 35 between these surfaces being thereby adjusted to suit the degree of juice extraction desired. In the event of an excessive pressure on the pomace in passing through this annular discharge passage 35, the screw is yieldingly permitted to move toward the right, as viewed in Fig. 2, so as to relieve this excessive pressure and avoid the danger of breakage or of stopping the machine because of the excessive pressures involved. Thus, when an excessive pressure develops in the pomace discharge opening 35, the entire screw, together with its shaft extensions 21 and 22, moves to the right against the resistance of the helical compression spring 51, the shaft extension 22 sliding in the sleeve 47 and collar 45 to permit such relieving movement of the screw 20. After the conditions of excessive pressure in the pomace discharge opening 35 have been relieved, the helical compression spring 51 draws the shaft 22, 21 together with the screw 20 back to the left as viewed in Fig. 1 to the position of adjustment determined by the setting of the adjusting sleeve 66 through the hand wheel 69, as previously described. The effective pressure of the helical compression spring 51 in so permitting a relief movement of the screw 20 to avoid excessive pressures in the pomace discharge opening 35 is readily adjusted through the adjusting nut 52 against which the end of the helical compression spring 51 bears, this adjusted position of the nut 52 being maintained by the lock nut 56.

The screw 20 illustrated is of unusually large diameter, that is, in the order of twelve inches in diameter. With a screw of this size it has been found necessary, especially when handling unusually pulpy materials, to provide additional pressure against the pomace being discharged through the annular discharge opening 35 beyond that which can be obtained from the trailing end of a single screw thread. For this purpose the auxiliary screw thread 40 is provided in the trailing convolution of the groove 26, the trailing end of this auxiliary thread 40 acting in the same manner as the trailing end of the main thread 25 of the screw and serving substantially to double the pressure imposed upon the pomace being forced through the annular pomace discharge opening 35.

From the foregoing it will be seen that the present invention provides a juice extractor of the screw type which is particularly applicable to screws of exceptional diameter and of corresponding high capacity. It will also be seen that a simple means is provided for readily adjusting the position of the screw to vary the effective size of the pomace discharge opening and hence the degree of juice extraction obtained. It will further be seen that the invention provides a

simple overload relief means which prevents the building up of excessive pressures at the pomace discharge opening and that the bearing associated with the adjusting mechanism and the overload relief mechanism is of a self-aligning type which insures uniform and smooth operation of the apparatus at all times.

I claim as my invention:

1. In a juice extractor having a fixed end head, a rotatable screw having a coaxial end shaft journaled in said end head and having one end tapered and means cooperating with said tapered end to provide a restricted annular pomace discharge opening, the passage of pomace through which produces an axial pressure against said screw; adjusting means for varying the effective size of said pomace discharge opening, comprising an adjusting sleeve surrounding said shaft, means for mounting said adjusting sleeve on said end head and permitting said adjusting sleeve to be moved axially to different positions, a thrust bearing including an inner race slidably mounted on said shaft and an outer race fast to said adjusting sleeve, said shaft being provided with spaced abutment means on opposite sides of said inner race and a helical compression spring surrounding said shaft and interposed between said inner race and the outermost of said abutment means and yieldingly permitting axial movement of said shaft and screw upon the building up of excessive pressure in said annular pomace discharge opening by the pomace being forced therethrough by said screw.

2. In a juice extractor having a fixed end head, a rotatable screw having a coaxial end shaft journaled in said end head and having one end tapered and means cooperating with said tapered end to provide a restricted annular pomace discharge opening, the passage of pomace through which produces an axial pressure against said screw; adjusting means for varying the effective size of said pomace discharge opening, comprising an adjusting sleeve threadedly mounted on said end head and surrounding said shaft, a self-aligning thrust bearing including an inner race slidably mounted on said shaft and an outer race fast to said adjusting sleeve, said shaft being provided with spaced abutment means on opposite sides of said inner race and a helical compression spring surrounding said shaft and interposed between said inner race and the outermost of said abutment means and yieldingly permitting axial movement of said shaft and screw upon the building up of excessive pressure in said annular pomace discharge opening by the pomace being forced therethrough by said screw.

3. In a juice extractor having a fixed end head, a rotatable screw having a coaxial end shaft

journaled in said end head and having one end tapered and means cooperating with said tapered end to provide a restricted annular pomace discharge opening, the passage of pomace through which produces an axial pressure against said screw; adjusting means for varying the effective size of said pomace discharge opening, comprising an adjusting member mounted on said end head adjacent said shaft and movable in a direction generally parallel with said shaft, and means mounted on said adjusting member and engaging said shaft to compel said shaft to move axially in either direction with said adjusting member and permitting rotation of said shaft.

4. In a juice extractor having a fixed end head, a rotatable screw having a coaxial end shaft journaled in said end head and having one end tapered and means cooperating with said tapered end to provide a restricted annular pomace discharge opening, the passage of pomace through which produces an axial pressure against said screw; adjusting means for adjusting said screw axially to vary the effective size of said annular pomace discharge opening, comprising an adjusting sleeve threadedly mounted on said end head and surrounding said shaft and a thrust bearing interposed between said adjusting sleeve and shaft and adapted to compel said shaft to move axially in either direction with said adjusting sleeve upon the manual rotation of said adjusting sleeve to positively effect an axial adjustment of said screw in either direction.

5. In a juice extractor having a fixed end head, a rotatable screw having a coaxial end shaft journaled in said end head and having one end tapered and means cooperating with said tapered end to provide a restricted annular pomace discharge opening, the passage of pomace through which produces an axial pressure against said screw; adjusting means for adjusting said screw axially to vary the effective size of said annular pomace discharge opening, comprising an adjusting sleeve threadedly mounted on said end head and surrounding said shaft, a thrust bearing interposed between said adjusting sleeve and said shaft and adapted to compel said shaft to move axially in either direction with said adjusting sleeve upon the rotation of said adjusting sleeve to effect the positive axial adjustment of said shaft and screw in either direction, and a helical compression spring interposed between said bearing and an abutment on said shaft and yieldingly permitting axial movement of said screw upon the building up of excessive pressure in said annular pomace discharge opening by the pomace being forced therethrough by said screw.

WILLIAM DE BACK.
